UNITED STATES PATENT OFFICE.

HAROLD E. AUSTIN, OF LOUISVILLE, KENTUCKY, AND JESSE C. COOK, OF JEFFERSONVILLE, INDIANA, ASSIGNORS TO AMERICAN CREOSOTING COMPANY, OF LOUISVILLE, KENTUCKY, A CORPORATION OF INDIANA.

PLATFORM FOR TIMBER-PRESERVING CYLINDERS.

Application filed December 8, 1922. Serial No. 605,727.

To all whom it may concern:

Be it known that we, HAROLD E. AUSTIN, of Louisville, in the county of Jefferson, State of Kentucky, and JESSE C. COOK, of 5 Jeffersonville, in the county of Clark, State of Indiana, have invented certain new and useful Improvements in Platforms for Timber-Preserving Cylinders; and we do hereby declare the following to be a full, 10 clear, and exact description of the invention, such as will enable others skilled in the art to which it appertains to make and use the same.

In cylinders used in timber impregnation 15 and other arts where such containers are subjected to high internal pressure the fastening of the doors in a manner to prevent leakage of the fluid under pressure and unfastening the doors for discharge is attended 20 with great difficulty because of the size of the doors used with such cylinders and the heavy wrenches required for manipulating the fastening means. These cylinders being of a height requiring the operator to take an 25 elevated position to get to the fastening elements, simple wooden benches have heretofore been employed to that end, these benches being carried by hand to the place where used and then removed so that the 30 door may be opened without interference. Such benches have, necessarily, been of substantial construction and of a weight making movement a difficult task. It is the object of our invention to provide a simple and 35 effective door platform which may readily be brought into position to allow the operator to reach the highest point of the cylinder door without undue exertion and after fastening or unfastening the door be swung 40 from its operative position to a point where it will not offer interference to the opening or closing movements of the door.

Figure 1 is a top plan view of the outer end of a wood impregnating cylinder 45 equipped with our improved platform. Figure 2 is a front elevation and Figure 3 is a view in side elevation of the device.

Our invention comprehends the idea of so constructing a platform for timber preserving cylinders and connecting it with such cylinders that its different positions relative to the cylinder are controlled wholly by the weight of the different parts of the platform.

Uprights 1 and 2 are arranged at each 55 side of the cylinder A and connected by a truss 3 so as to give a maximum rigidity thereto. Extending rearwardly from the upper portion of these uprights are members 4 upon which the deck 5 is supported. Beams 60 6 extend in an upwardly and rearwardly inclined direction from the uprights 1 and 70 form, with the members 4, a triangular frame. Each beam preferably comprises two channel bars riveted together and reinforced at 65 the point 7, which is somewhat removed from the longitudinal center of the beam, to receive a stud 8 seated in a casting 9 which 75 is riveted to the side of the cylinder, the beam being free to turn about said pivot. The forward and longer portion of each beam beyond its connection with the cylinder is offset from the rear portion so as to give a greater span between beams at the outer end. The rear end of each beam, 80 which is the shorter end, has a weight 10 suspended therefrom which is adapted to counterbalance the parts when the platform is in a raised position. Additional support is given the deck timbers, especially those 85 next adjacent the cylinder head B, by angle irons 12 projecting divergently from the members 4, and we have shown short ladder lengths 13 at each side of the platform.

The adaptability of our improved platform is clearly manifest. In the position shown in each of the figures of the drawings access may readily be had from the platform to the highest point of the cylinder door for the purpose of fastening or unfastening the bolts by which the door is secured to its cylinder and when this work is accomplished the platform is easily swung upwardly, but little force being necessary to lift it to the point slightly beyond perfect 90 balance so that the counterweight 10 will overbalance the platform portion and maintain the latter in elevated position without danger of falling. The platform is as readily brought into operative position by moving the counterweight upwardly. 100

We claim as our invention:

1. In combination with a timber preserving cylinder, and a door therefor, a platform, and counterbalanced means for swingingly 105 supporting the platform for movement to and from the path of opening movement of the door.

2. A hinged platform comprising pivotally mounted side beams counterbalanced at one end, uprights connected to the opposite ends of the beams, a transversely arranged truss connecting the uprights, and a platform supported by the truss, the beams and the uprights.
3. In combination with a timber preserving cylinder, a platform including side beams pivotally connected with opposite sides of said cylinder, and means acting on said beams to overbalance the weight of said platform in one position thereof, said platform movable across the end of the cylinder.
4. In combination with a timber preserving cylinder, a platform including supporting uprights, beams extending upwardly and rearwardly from said uprights and having a pivotal connection with said cylinder at a point beyond the longitudinal center of said beams, a member connecting the upper end of each upright with its complementary beam, such members forming a deck support, and a weight on the free end of each beam to overbalance said platform when in raised position.
5. A hinged platform for timber preserv-

ing cylinders, comprising counterbalanced beams adapted to be pivoted to the opposite sides of a cylinder and offset outwardly at their outer end portions to provide clearance space for swinging over the forward end of the cylinder, uprights on the forward ends of the beams, a transverse truss bracingly connecting the uprights, deck supporting members connecting the upper ends of the uprights to their respective beams, and a deck on the supporting members.

6. A movable platform for timber preserving cylinders, comprising side beams adapted to be pivotally supported on a cylinder, uprights carried by the forward ends of the beams, deck-supporting members connecting the upper ends of the uprights to the respective beams, deck timbers supported by said members, and auxiliary supporting means for the deck timbers consisting of forwardly convergent members connected at one end to the deck supporting members and at their opposite ends to one of the deck timbers.

In testimony whereof we have signed this specification.

HAROLD E. AUSTIN.
JESSE C. COOK.
